CLAIM

The ornamental design for a fishing rod buoyant, as shown
and described.

DESCRIPTION

FIG. 1 is a perspective view of a fishing buoyant float
showing my new design;FIG. 2 is a rear elevational view taken from the rear side of
FIG. 1;

FIG. 3 is a top plan view thereof;

FIG. 4 is a front elevational view thereof;

FIG. 5 is an elevational view taken from the right end of
FIG. 1, the left end elevational view being a mirror image
thereof; and,

FIG. 6 is a bottom plan view thereof.

The broken line showing the environment in FIG. 1, 3, 4 and
5 is for illustrative purposes only and forms no part of the
claimed design.
